AUTOMATIC GAIN CONTROL

Application filed October 29, 1929. Serial No. 403,281.

My present invention relates to an automatic gain or amplification control, and more particularly to an improvement in a gain control circuit of the type disclosed in 5 my co-pending application Serial No. 310,497 filed October 5th, 1928.

In the aforesaid co-pending application there has been disclosed an audio frequency amplifier whose gain varies inversely with 10 the input level so that a sudden increase in input is limited to a predetermined constant output. Briefly, the manner in which this is accomplished is by varying the anode load of an amplifier tube by automatically 15 adjusting the anode impedance of a control tube in a predetermined manner, said anode impedance being in parallel with the amplifier anode circuit, the uni-directional component of a rectified portion of the alternating 20 input current to be amplified being employed to secure the adjustment. Thus, the change in the anode load of the amplifier alters its amplification.

Now, by further experimentation various 25 improvements have been made upon the invention in the said co-pending application, it being observed that the present arrangement is primarily designed for, and has for its main object, a use where very sudden increases in input voltage, (due for example, 30 to a very sudden increase in volume during a musical program), may cause overloading to occur, and additionally, to augment rather than to supplant manual operation of a gain 35 control, since for sudden increase in input voltage the arrangement is faster than manual operation.

Another important object of the invention 40 is to provide an audio frequency amplifier including controlling equipment broadly comprising an amplifier, a rectifier, a control tube and a time control and filter arrangement for controlling the speed at which the impedance of the control tube 45 varies, the control equipment including a plurality of audio amplifier tubes, the plate circuits of the control tube and the first of said plurality of amplifier tubes being inductance coupled to maintain the plate voltages constant regardless of the impedance of 50

the control tube whereby the dynamic characteristic of the said plurality of amplifier tubes remain more constant during operation of the control tube.

Another object of the invention is to provide an amplifier circuit having a predetermined ratio between the input energy applied to the amplifier and the output energy derived therefrom which comprises a control equipment including a plurality of amplifier 55 tubes, the input to the last tube being obtained from a drop across a part of a load resistance connected in the output circuit of a control tube, the latter being supplied with a rectified portion of the alternating current 60 to be amplified, there being a condenser connected in series with said load resistance and forming the alternating current output circuit of the control tube, the system thereby being less likely to cause distortion, since 65 high resistance is always in the circuit regardless of the plate impedance of the control tube.

Still another object of the invention is to provide an audio amplifier whose output is 70 maintained substantially constant while the input is varied, means for accomplishing the latter result, said means being designed to respond quickly or slowly, as desired.

Other objects of the invention are to improve generally the simplicity and efficiency of automatic gain control devices for amplifiers, and to especially provide an automatic gain control for an audio amplifier, which is durable and reliable in operation, 80 and economical to manufacture.

The novel features which I believe to be characteristic of my invention are set forth in particularity in the appended claims, the invention itself, however, as to both its organization and method of operation will best be understood by reference to the following description taken in connection with the drawings in which I have indicated diagrammatically one circuit organization whereby 85 my invention may be carried into effect.

In the accompanying drawings,

Fig. 1 is a schematic diagram showing the equipment essential to an amplifier embodying the present invention,

Fig. 2 is a circuit diagram showing in greater detail the various elements of Fig. 1,

Figs. 3 and 4 are curves illustrating the manner in which the apparatus shown in Figs. 1 and 2 function,

Figs. 5 to 8 inclusive, are an analysis of the present improvement.

Referring to the accompanying drawings in which like characters of reference indicate the same parts in the different figures, there is fed into the apparatus, as shown in Figs. 1 and 2, at "input" a varying alternating input. A portion of this input is fed directly into the first amplifier tube 2 of the control equipment. Another portion of the alternating input is fed into an amplifier tube 3 of the controlling equipment, and thence into a rectifier 4. It is to be understood that, if desired, the amplifier tube 3 may be omitted.

The uni-directional component of the rectifier current is then fed into the time control and filter device 5. The latter controls the speed at which the bias on the control electrode of control tube 6 is varied by the changes in the uni-directional component of the rectified current.

Control tube 6 has its anode-cathode current supplied through the anode impedance 7. The first amplifier tube 2 of the control equipment has connected between its anode and cathode a resistance tapped at a point 16, the latter dividing the resistance into two portions R_1 , R_2 . The impedance 7, in this case a choke coil, is connected in series with the portion R_2 by means of a resistance R_1 , and in series with a condenser 10, the resistance R_1 having one of its terminals connected to point 16.

The anode of tube 2 is connected in series with the portion R_1 through a condenser 14. A second impedance 15, in this case also a choke coil, is connected in the anode circuit of the tube 2, anode current being supplied therethrough. The input to the last amplifier tube 2' is obtained from the drop across part of the grid leak resistance 13, which together with a series condenser 12, the latter having one of its terminals connected to point 16, forms the alternating current output circuit of the amplifier. It will also be observed that the portion of the input which is fed directly to the control amplifier tube 2 first passes through the resistance R_2 , R_3 .

In Fig. 2 I have shown in greater detail the connections and apparatus employed in the construction schematically shown in Fig. 1. The amount of the input energy applied to the controlling equipment amplifier 3 is varied by means of a manually controlled resistance 8, the output of the amplifier tube 3 being fed, by means of an audio transformer 9, into rectifier tube 4, the latter having a cathode of the heater type.

The control electrode and anode of the rectifier tube 4 are connected together forming a two element rectifier, used so as to produce a more nearly perfect rectilinear characteristic. The other portion of the input alternating energy is fed through a condenser 20 to the first amplifier tube 2 of the control equipment.

The time control and filter device 5 shown diagrammatically in Fig. 1 preferably comprises, in Fig. 2, a resistance 30, condenser 31, choke coil 32, variable resistance R and condenser 33. With a sufficiently large input the negative grid bias of control tube 6 is reduced so that controlling action results. That is, under those circumstances the internal impedance of the tube 6 is reduced, and, as its anode current passes through the anode impedance or choke coil 7 of the first control amplifier tube, a change occurs in the effective value of the anode impedance or load of tube 2 which latter consists of the impedance 15, and resistances R_2 , R_3 , in parallel with the control tube 6. The latter effect lessens the amplifying effect of tube 2 on the input supply to it through condenser 20.

The speed of control is varied by varying resistance R . The reason why variation of resistance R will control the speed of operation of the apparatus may be explained as follows: When a high input which has been applied is suddenly removed, and assuming that the condensers 31 and 33 remain charged, the charge on condenser 31 can only discharge through high resistance 30, if the impedance of the rectifier tube 4 is high. Condenser 33 can only discharge through the series combination of variable resistance R , choke 32, and resistance 30, since the internal impedance of the control tube is also high.

When the rectifier impedance is low, as for example, when a large voltage is supplied by transformer 9 to rectifier 4 then the charge on condenser 31 can leak off across it. However, condenser 33 will still have to discharge through resistance R which may be varied to control its speed of discharge. Hence, the speed at which the bias on the control electrode of the tube 6 may be varied, is secured by the manipulation of resistance R .

When a strong signal is applied to the controlling amplifier tube 3, condensers 31 and 33 will become highly charged and because of the reduced control electrode or negative grid bias on tube 6, control tube 6 will have its impedance reduced. If this strong signal is suddenly cut off the impedance of rectifier 4 will increase rapidly. Condensers 31 and 33 will retain their charge until resistors 30 and R discharge them.

As a result, the control tube grid bias will

remain nominally reduced and the amplification of control amplifier tube 2 low. A resistance R_4 , the latter being of a higher order of magnitude than resistance 30, is disposed across the anode-cathode circuit of rectifier tube 4 and decreases the time of discharge in this case, and makes the controlling action more uniform. Of course, the speed of action can still be manually controlled by adjusting the resistance R which determines the discharge rate of condenser 33.

A milliammeter A is disposed in the output circuit of control tube 6 to indicate its operation. The amount of control is indicated by the milliammeter which is mounted on the front panel of the receiver. When the latter is reading zero, the control tube is not acting; when it reads 2.5 milliamperes, then the control tube is acting to its full capacity. The meter, in other words, reads the control tube plate current.

As the control device does not operate from the output voltage (as in the case of certain radio frequency automatic gain controls) it is necessary to carefully adjust the various resistances, so that the output remains substantially constant. The resistance R_1 prevents "over control" which will occur if the control tube plate impedance becomes too low compared to R_2 . If R_1 is too high, insufficient control will be obtained. The resistance R_3 is placed in the amplifier plate circuit to prevent distortion which would otherwise occur when the control tube plate impedance becomes too low.

As indicated heretofore, the high resistance R_4 is employed to allow the filter condenser charge to leak by the rectifier tube when the voltage employed is low and the rectifier impedance is high. When a high voltage input is applied, the rectifier impedance is low and this resistance is not needed. The effect of this phenomenon is to allow the control to act rapidly in cutting off the gain when high inputs are applied but to tend to "hangover" after the high input has decreased.

The resistance R_4 has been selected to partially prevent this. It has been noted that when a high input is applied, and then removed, the milliammeter reading increases rapidly, decreases rapidly at first, and becomes slower and slower as the reading decreases. The time action control allows individual variations, or sudden checks to be controlled by making the action fast; or to control merely the general level by making the action slow.

It may be found necessary to place a grounded shield between the rectifier tube 4 and the control tube 6 to prevent distorted signals from getting into the output amplifier. The amplifier is designed to operate between a 200 ohm input and 500 ohm load,

which may be readily adapted to other input and output impedances.

The system is, further, provided with a switch, generally denoted by S, that facilitates connecting the input directly to the output without being controlled. This may be desirable if for any reason the system should cease to function properly. The system may then be disconnected and the manual control of the input utilized until the trouble is rectified.

The main plate battery employs a voltage of 135 volts, the voltages indicated in Fig. 2 being those which have been found to be satisfactory in practice. Resistances 20' are used to obtain correct voltages for the tube filaments. The positive A connection is preferably grounded and connected to the positive C and negative B.

The control acts by shunting the plate impedance of a tube across a portion of a coupling impedance in an impedance capacity coupled amplifier. The plate impedance of the tube is changed in accordance with the input level by amplifying some of the input, rectifying it, and applying the direct current component as grid bias for the control tube. It will be noted that only a single stage of amplification is employed before rectification instead of the two stages of amplification as disclosed in my abovementioned co-pending application. One stage has been found sufficient to deliver the necessary output to operate the control tube satisfactorily.

The actual amplifier from which the output is taken is the equivalent of a two stage amplifier and has a gain of about 30 decibels, when the control is not acting. Its gain may be varied manually, of course, by the control 13. The control will begin to act when an input of about 15 millivolts is applied, when the control gain is set at maximum. If the control gain is reduced, higher inputs are required before the control acts.

The control action has little effect on the frequency amplification, as is well shown in Fig. 3 which graphically illustrates the characteristics for full and no control. The frequency characteristic in Fig. 3 indicates that there is practically no change produced in relative amplification of high and low tones when the control is working, or when it is not, i. e.; it does not produce frequency distortion. The ordinates of this curve are expressed in "deci-bells", (d. b.) which name is now superseding the older one of "transmission units" (t. u.).

The control action is also shown in Fig. 4 which graphically represents output voltages for various inputs and different degrees of control. The input-output curve in Fig. 4, shows that without control, the output increases proportionately with input as far as the curve has been plotted. With control 13

however, the output at first increases proportionately and then remains substantially constant at some value determined by the circuit constants.

5 Finally, it is to be noted that one of the major differences between the present arrangement and that described in my co-pending application involves the fact that the plate circuits of the control and amplifier tubes of the present arrangement are inductance coupled rather than resistance coupled. This tends to maintain the plate voltages constant regardless of the impedance of the control tube. This results in the maintenance of the dynamic characteristic of the tubes more constant during operation of the control tube 6.

Again, another important difference and improvement involves the fact that the input to the last amplifier tube 2' of the control equipment is obtained from the drop across part of the load resistance 13 which together with series condenser 12, forms the alternating current output circuit of the amplifier. By the use of this improved method the system is less likely to cause distortion since a resistance of at least 48,000 ohms is always in the circuit regardless of the plate impedance of the control tube 6.

30 To analyze these differences in more detail it will be noted that in an ordinary amplifier circuit, without the volume control principle, for the tube 2', would consist of the tube, its plate load impedance 15', a grid leak 13', and a stopping condenser 12'. In this arrangement, the total voltage drop across the impedance 15' would be applied to the grid of the succeeding tube, 2. (See Fig. 5.) If now a resistance is shorted 40 across the plate load 15', the amplification of tube 2' will vary according to the value of the load. If this resistance is made to vary inversely as the amplitude of the applied signal voltage, a more or less uniform 45 output will be obtained from a varying input.

If such a load is introduced, in the form of the plate impedance of a vacuum tube, it will be necessary to isolate its plate circuit 50 from the grid circuit of the tube 2. (See Fig. 6.) This is done by the grid blocking condenser 12'. It will be noted that the anodes of tubes 2' and 6 are in parallel and that if a larger positive bias is applied to 55 the grid of tube 6 (caused by a strong signal being applied and hence a large rectified component being present), the voltage drop across 15' will increase, which action will reduce the anode voltage on tube 2'. This 60 is essentially the circuit described in my aforementioned co-pending patent application. Such variation in plate voltage will cause distortion of the output wave form.

If however, the plate voltage supply of 65 controlled tube 2', and control tube 6, can

be made independent, this distortion will no longer be present. Furthermore, individual tube adjustments can be made without affecting other tubes. The present improved circuit is analytically shown in Fig. 7. 70 Here, 12' and 10' are plate blocking condensers, and the tubes 2' and 6 are supplied through individual anode loads, 15' and 7' respectively. These loads may be either resistances or inductances, preferably the latter. Load 15' may be considered as the coupling impedance between tubes 2' and 2.

75 It has been found in practice that the plate impedance of tube 6 becomes lower more rapidly than it should for maintaining constant output. To avoid this, the plate impedance of tube 6 is shunted across only a portion of the plate load of tube 2'. This is accomplished by means of the potentiometer R_2 , R_3 . (See Fig. 8.) Resistance R_1 is used to prevent the plate circuit impedance 80 of tube 6 from decreasing to too low a value.

85 It is to be understood that while the invention is especially adapted for use with audio frequency currents, it may, if desired to be utilized in a radio frequency amplifying system. Furthermore, while I have indicated and described one arrangement for carrying my invention into effect, it will be apparent to one skilled in the art that my 90 invention is by no means limited to the particular organization shown and described, but that many modifications may be employed, without departing from the scope of my invention as set forth in the appended 95 claims.

100 What I claim is:

1. In an amplifying system, an electron discharge tube comprising an anode, a cathode and a control electrode, means to apply 105 alternating current energy variations to said tube, means for rectifying a portion of the alternating current energy to be amplified by said tube, means including a control tube to vary the effective anode load of said first 110 tube according to the amplitude of the rectified current, and a common path, including a pair of inductances, for applying a positive potential to the anodes of the first 115 tube and the control tube.

2. In an amplifying system, an amplifier tube, means to apply alternating current to the control electrode of said tube, means for producing a direct current whose value is determined by the amplitude of said alternating current, means including an electron discharge tube to apply said direct current to said amplifier tube to control the anode potential thereof, and means for applying a desired positive potential to the anodes of the amplifier tube and said electron discharge tube, said means including a choke coil connected to each of said last mentioned anodes.

120 3. An alternating current amplifier com- 130

prising a tube having an anode, cathode, and control electrode, an impedance in the anode circuit of said tube, another tube shunting said impedance, means for applying a portion of the alternating current to said first tube, means for rectifying another portion of said alternating current, means for applying to the control electrode of the tube shunting said impedance, the direct current component of said rectified alternating current and a capacitative path connecting the anode of said first tube with the high potential side of said impedance.

4. An audio frequency amplifier comprising a tube, a choke coil connected to the anode of said tube, a control tube shunting said choke coil, means for applying a portion of an alternating current to be amplified to the control electrode of said first tube, means for rectifying another portion of said alternating current, means for applying the uni-directional component of the rectified current to the control electrode of said control tube whereby the anode impedance of said first tube is varied in accordance with the strength of the rectified current.

5. An audio frequency amplifier comprising a tube, a choke coil connected to the anode of said tube, a control tube shunting said choke coil, means for applying a portion of an alternating current to be amplified to the control electrode of said first tube, means for rectifying another portion of said alternating current, means for applying the uni-directional component of the rectified current to the control electrode of said control tube whereby the anode impedance of said first tube is varied in accordance with the strength of the rectified current, and a capacitative path connecting the high potential side of said choke coil with the anode of said first tube.

6. In an amplifier system, an amplifier tube, means to apply an alternating current to be amplified to the input of said tube, means for rectifying a portion of the alternating current to be amplified by said tube, a control tube to vary the effective anode load of said amplifier tube according to the amplitude of the rectified current, means to control the speed at which said anode load is varied, and a capacitative path connecting the anodes of the control tube and amplifier tube.

7. In an amplifier system, an amplifier tube, means to apply an alternating current to be amplified to the input of said tube, means for rectifying a portion of the alternating current to be amplified by said tube, a control tube to vary the effective anode load of said amplifier tube according to the amplitude of the rectified current, means to control the speed at which said anode load is varied, a capacitative path connecting the anodes of the control tube and amplifier

tube and a resistor connected between a point on the capacitative path and the cathodes of the control tube and amplifier tube.

8. In an amplifier system, an amplifier tube, means to apply an alternating current to be amplified to the input of said tube, means for rectifying a portion of the alternating current to be amplified by said tube, a control tube to vary the effective anode load of said amplifier tube according to the amplitude of the rectified current, means to control the speed at which said anode load is varied, a capacitative path connecting the anodes of the control tube and amplifier tube, a second amplifier tube, and an adjustable path, including a condenser, connected between the grid of the second amplifier tube and a point on said capacitative path.

9. An audio frequency amplifier comprising a multi-electrode amplifier tube, a choke coil in the anode circuit of said amplifier tube, a multi-electrode control tube, a choke coil connected to the anode of said control tube, means for connecting both said choke coils to a source of positive potential, means for applying a portion of an alternating current to be amplified to the control electrode of said amplifier tube, means for rectifying another portion of said alternating current, means for applying the uni-directional component of the rectified current to the control electrode of said control tube whereby the anode impedance of said amplifier tube is varied, in accordance with the strength of the rectified current, means for controlling the speed at which said anode impedance varies, said means including a variable resistance and a condenser, a capacitative path connecting the high potential sides of said choke coils, a resistor connected between a point on the capacitative path and the cathodes of the control tube and said amplifier tube, a second amplifier tube, and an adjustable path, including a condenser, connected between the grid of the second amplifier tube and a point on said capacitative path.

10. In an amplifying system, an electron discharge tube including a plurality of electrodes, means to apply alternating current to the control electrode of said tube, means for producing a direct current whose value is determined by the amplitude of said alternating current, a control tube to apply said direct current to said first tube to control the anode potential thereof, and a network including lumped inductive and condensive impedances connecting the anode and cathode of said first tube with the anode and cathode of said control tube.

11. In an amplifying system, an electron discharge tube including a plurality of electrodes, means to apply alternating current to the control electrode of said tube, means

for producing a direct current whose value is determined by the amplitude of said alternating current, a control tube to apply said direct current to said first tube to control 5 the anode potential thereof, a network including lumped inductive and condensive impedances connecting the anode and cathode of said first tube with the anode and cathode of said control tube, and means to 10 control the rate at which said anode potential is varied.

12. In an amplifying system, an electron discharge tube including a plurality of electrodes, means to apply alternating current 15 to the control electrode of said tube, means for producing a direct current whose value is determined by the amplitude of said alternating current, a control tube to apply said direct current to said first tube to control 20 the anode potential thereof, a network including lumped inductive and condensive impedances connecting the anode and cathode of said first tube with the anode and cathode of said control tube, a second amplifier tube and an adjustable impedance path, including a condenser connecting the grid of said second amplifier tube to a point on 25 said network.

13. In combination, in an automatic gain 30 control circuit for an amplifier, an amplifier tube having its input electrodes connected to a source of energy to be amplified, a gain control tube, a common path for connecting the anodes of said amplifier and control 35 tubes to a source of positive potential, means for impressing on the input of said control tube control energy derived from said source whereby the internal impedance of said control tube is adjusted in a predetermined 40 manner with respect to variations of said source energy, and a capacitative path, independent of said common path, connecting the anodes of said control tube and amplifier tube.

45 14. In combination, in an automatic gain control circuit for an amplifier, an amplifier tube having its input electrodes connected to a source of energy to be amplified, a gain control tube, a common path for connecting 50 the anodes of said amplifier and control tubes to a source of positive potential, means for impressing on the input of said control tube control energy derived from said source whereby the internal impedance of said control tube is adjusted in a predetermined 55 manner with respect to variations of said source energy, a capacitative path, independent of said common path, connecting the anodes of said control tube and amplifier 60 tube, and a resistor connected between a point on said capacitative path and the cathodes of said amplifier and control tubes.

65 15. In combination, in an automatic gain control circuit for an amplifier, an amplifier tube having its input electrodes con-

nected to a source of energy to be amplified, a gain control tube, a common path for connecting the anodes of said amplifier and control tubes to a source of positive potential, means for impressing on the input of 70 said control tube control energy derived from said source whereby the internal impedance of said control tube is adjusted in a predetermined manner with respect to variations of said source energy, a capacitative path, independent of said common path, connecting the anodes of said control tube and amplifier tube, said capacitative path including a resistor and a second resistor connected between an intermediate point of 75 said last mentioned resistor and the cathodes of said amplifier and control tubes.

16. In combination, in an automatic gain control circuit for an amplifier, an amplifier tube having its input electrodes connected 85 to a source of energy to be amplified, a gain control tube, a common path for connecting the anodes of said amplifier and control tubes to a source of positive potential, means for impressing on the input of said control 90 tube control energy derived from said source whereby the internal impedance of said control tube is adjusted in a predetermined manner with respect to variations of said source energy, a capacitative path, independent of said common path, connecting the anodes of said control tube and amplifier tube, a second amplifier tube, a resistor connecting the cathodes of said first amplifier tube and control tube to a point on said 95 capacitative path, and an adjustable impedance path connecting the grid of said second amplifier tube and said last mentioned point.

17. In an amplifying system, an electron discharge tube comprising an anode, a cathode and a control electrode, means to apply alternating current energy variations to said tube, means for rectifying a portion of the alternating current energy to be amplified by said tube, means including a control tube to vary the effective anode load of said first tube according to the amplitude of the rectified current, a common path, for applying a positive potential to the anodes of the first tube and the control tube, and a switch mechanism for disconnecting or connecting at will the said rectifying means and control tube and the said first tube.

18. In an amplifying system, an electron discharge tube comprising an anode, a cathode and a control electrode, means to apply alternating current energy variations to said tube, means for rectifying a portion of the alternating current energy to be amplified by said tube, means including a control tube to vary the effective anode load of said first tube according to the amplitude of the rectified current, a common path, 125 including a pair of inductances, for apply- 130

ing a positive potential to the anodes of the first tube and the control tube and a switch mechanism for disconnecting or connecting at will the said rectifying means and control tube and the said first tube.

- 5 19. In an amplifying system, an electron discharge tube comprising an anode, a cathode and a control electrode, means to apply alternating current energy variations to said tube, means for rectifying a portion of the alternating current energy to be amplified by said tube, means including a control tube to vary the effective anode load of said first tube according to the amplitude 10 of the rectified current, a common path for applying a positive potential to the anodes of the first tube and the control tube, a load circuit coupled to the anode of said first tube, manually operable means for varying 15 the transfer of energy between the anode circuit of said first tube and said load circuit, and a switch mechanism for disconnecting or connecting at will the said rectifying means and control tube and the said 20 first tube.

- 25 20. In an amplifying system, an electron discharge tube comprising an anode, a cathode and a control electrode, means to apply alternating current energy variations to said tube, means for rectifying a portion of the alternating current energy to be amplified by said tube, means including a control tube to vary the effective anode load of said first tube according to the amplitude 30 of the rectified current, a common path, including a pair of inductances, for applying a positive potential to the anodes of the first tube and the control tube, and a visual 35 current indicator connected in the anode circuit of said control tube.
